UNITED STATES PATENT OFFICE

NICHOLAS J. CONRAD, OF WILMETTE, ILLINOIS, ASSIGNOR, BY MESNE ASSIGNMENTS, TO SCHWEITZER & CONRAD, INC., OF CHICAGO, ILLINOIS, A CORPORATION OF DELAWARE

RESISTANCE UNIT

Application filed January 30, 1928. Serial No. 250,507.

My invention relates to resistance units employed as protective devices in circuits such as the primary circuits of potential transformers in electric power stations. While the invention is described in connection with the aforesaid use, it is to be understood that the invention is not to be limited to such use, but may be employed wherever found suitable.

As explained in my co-pending application, Serial No. 244,015, filed December 31, 1927, potential transformers which are applied to the synchronizing, indicating and recording of alternating current, must necessarily be connected directly to the main buses. In this location their failure would hazard the buses and generating or transformer equipment unless reliable protection is installed. Whereas, it is customary to put a fuse in the circuit of such potential transformers to interrupt any excessive flow of current, it has been found highly advisable to insert a protective resistance in addition to the fuse in series with such potential transformers to limit the possible flow of current upon a short circuit at or near the primary terminals of the transformer. The use of such a resistance limits the short circuit current without appreciably disturbing the accuracy of the potential transformer as a part of an indicating circuit. That is to say, in the preferred form of my invention, the 60-cycle impedance is practically the same as the resistance. The primary voltage drop is less than two volts on 6600 to 132000 volts of potential transformer installation when the potential transformer is carrying a load of 200 volt amperes. Therefore the effect of this resistor on meter accuracy is negligible.

In the preferred form of my device I employ a helical coil of nickel chromium resistance wire wound on a wet process porcelain core, and the whole is enclosed in a glass walled container comprising a sleeve with conducting ferrules which seal the ends of the tube and form the terminal contacts. By mounting the resistance in this manner and enclosing it in glass, the resistor is housed against all weather conditions and may be used outdoors as well as indoors, and yet it

may be inspected without removing it from service. This embodiment of the invention also permits the mounting of the resistor in standard mountings such as are now employed for fuses, so that the problem of satisfactorily mounting the resistor is solved by adequate means now at hand.

In order to acquaint those skilled in the art with the manner of constructing and operating a device embodying my invention, I shall describe the same in connection with the accompanying drawings, in which a specific embodiment is disclosed.

In the drawings:

Fig. 1 is a side elevational view of a resistor embodying my invention;

Fig. 2 is a top plan view of the same;

Fig. 3 is a bottom plan view of the same;

Fig. 4 is a longitudinal cross section parallel to the plane of the paper in Fig. 1;

Fig. 5 is an end view with the cap or cover removed showing one terminal connection;

Fig. 6 is a fragmentary longitudinal view of a modification showing the manner in which a series of resistance units may be mounted in the same container;

Fig. 7 is a transverse cross-sectional view taken on the line 7-7 of Fig. 6;

Fig. 8 is a longitudinal section like that in Fig. 4, showing a modified form of the invention;

Fig. 9 is an end view, and Fig. 10 a side view, of a detail element for making connection between the wire resistance and the terminal and for supporting the end of the porcelain sleeve; and

Fig. 11 is a longitudinal cross section through a modified form of resistance unit adapted for carrying a larger current flow and presenting a lower resistance.

As shown in Fig. 1, the resistance unit of my invention comprises a glass sleeve 1 upon one end of which there is cemented the cap ferrule 2 comprising a brass cup-shaped element of exterior cylindrical form having its sides slabbed off as indicated at 3-3 in Fig. 3. The opposite end of the sleeve has a sleeve ferrule 4 which has a part of the sides slabbed off, as indicated at 5-5 in Fig. 2, to provide the shoulders 6-6.

These shoulders are adapted to engage the arms of a spring mounting such as is employed for mounting fuses of the type manufactured by Schweitzer & Conrad and sold on the open market as the "S & C fuse". In fact, in external construction the resistance unit is substantially identical with the well known "S & C fuse" and is adapted to be mounted in the same mounting which will support and connect the said "S & C fuse".

10 The sleeve 1 is cemented to the ferrules 2 and 4 by a fusible metal indicated at 7-7, to provide a gas tight seal. Obviously, other materials may be used to secure this result of securing the brass ferrules upon the ends 16 of the glass sleeve.

15 The upper ferrule 4 has a thickened wall indicated at 8 in Fig. 4 providing a conical shoulder 9 flaring outwardly, and an annular recess 10 defined by the flange portion 11.

20 The end of the upper ferrule 4 is closed by a sealing disc 12 which has a central arched or outwardly bulged portion and a flat radial portion 13 and a cylindrical flange 14 embracing the inner surface of the flange 25 11 and lying in the annular recess 10. This closure or plug 12 is preferably made of sheet metal and it may be pressed into place after the other parts, hereafter to be described, are inserted in the housing which is 30 formed by the glass tube and the attached ferrule.

25 A body of insulating material, in the present case wet process porcelain, 15 in the shape of a hollow rod having a helical groove on the outside of the same is disposed within the glass sleeve 1. At its ends the hollow rod or tube has transverse openings 16 at one side of the bore 17 in the hollow rod 15, and 35 larger transverse openings 18 on the opposite side of the bore 17 and in alignment with said openings 16.

40 The core 15 is provided with metallic mounts, in this case comprising short rods 19-19, of cylindrical form slabbed off at 45 their sides for a short length to provide a flat seating surface for the heads of the terminal screws 20-21 which are threaded through the mounts 19-19. These rods 19-19 extend out of the end of the bore 17, 50 and the outer ends are threaded. The rod 19 at the inner end of the core 15 is threaded into a threaded boss 23 formed on the inside of the bottom of the cap ferrule 2.

55 A wire resistor comprising a helical coil of nickel chromium resistance wire is wound about the core 15 being disposed in the grooves 24 thereupon, and the ends of the wire are fastened under the heads of the screws 20 and 21, whereby the mounts 19-19 become not only the mechanical support for the core 15, but electrical terminals 60 for the resistor 25.

65 The resistor 25 is, in the present instance, a relatively small size wire wound in the

form of a helical coil of small diameter, like a coiled spring, and then the coil is wound in the grooves 24 on the core 15, the groove 24 being a continuous helical groove.

70 Threading of the mount 19 at the right of Fig. 4 in the boss 23 in the cap 2 connects the adjacent end of the resistor with the cap ferrule 2 for external connection. The mount 19 at the opposite end extends through a mounting spider 26, which, in this case, comprises merely a strip or flat bar having the ends 27 thereof turned up to fit the shoulder 9 and secured to the body of the ferrule 4 as by means of the machine screws 28-28.

75 The said spider 26 has a hole at the center 80 loosely embracing the aforesaid mount 19. If desired, the bar 26 may be threaded upon the threaded end of the rod mounts 19. I depend upon electrical connection between the mounts 19 and the ferrule 4 to be made by a flexible metallic braid 30, through the central part of which a machine screw 31 is passed and threaded into the end of the rod mount 19. A washer 32 lies under the braid 30 to prevent cutting of the same against the 85 end of the rod 19.

90 The ends of the braid 30 are connected to the sloping shoulder 9 by small machine screws 33. Now it will be seen that by the loose mounting of the mounting rod 19 in the 95 spider 26, the expansion and contraction of the core, due to heating and cooling, is free to occur without stressing either the mechanical mounting or the electrical connection. 100

95 The cover member 12 is preferably secured in place by cementitious material which hermetically seals the casing.

100 Due to the fact that the sleeve 1 is made of glass, inspection of the condition of the resistor is facilitated.

105 The device is mounted in spring jaws of the character disclosed in my Patent No. 1,665,446 dated April 10, 1928 with the shoulder 6 bearing against the jaws to support the 110 weight of the device in the mounting. The unit is prevented from dropping out of the mounting or being accidentally displaced from the same by wire bails which overhang the ends of the spring jaws.

115 The device illustrated in Figs. 1 to 4, when made for use in connection with a potential transformer on 7500 volts, has a resistance of 45 ohms and is intended to be connected in series with a fuse having a rating of $1\frac{1}{2}$ ampere. In that case the entire length of the 120 device is approximately $13\frac{1}{4}$ inches, the resistor comprising No. 20 Brown & Sharpe gage nichrome No. 4 wire, approximately 75 feet in length wound first on a $3\frac{1}{2}$ inch arbor, and then wound on the core 15, which is 125 approximately 1 inch in diameter.

130 Where a greater length of resistance wire is employed, as for example on 37000 volts, the glass sleeve 1 is necessarily longer and the

resistor should be longer. In that event, two cores with resistors thereupon are connected together in series within the sleeve 1, as indicated in Fig. 6. In that case the mounting rod 19 at the right hand end of the first core 15, and a like mounting rod 36 of the second core 35, are connected by a threaded block of metal 37. This connecting block has a series of pins 38, in this case three in number, extending radially outwardly into contact with the walls of the glass tubing 1 to support the compound resistor at the joint, which is approximately at the center of the sleeve 1.

These pins 38 lie in radial bores which are intersected by threaded openings 39 extending longitudinally of the block 37 with small pointed set screws 40 adapted to engage the inner ends of the pins 38 for holding the same in extended position to minimize the play which the block 37 may have with respect to the sleeve 1. The pins 38 are projected outwardly so that they fit substantially snugly the inside of the tube 1, to prevent any lost motion at this point which would permit the resistor or the core 15 to come in contact with the glass, or allow rattling of the device to strike the inside of the tube 1. The two mountings 19 and 36, which form the electrical terminals of the respective resistors 25 and 42, respectively, are connected together in series by the said block 37.

In Fig. 8 I have shown a unit in which the metallic mounting for the ends of the insulating rod 43 are formed in the shape of caps 44 and 45. These caps are identical in construction and comprise flanges overhanging grooves 46 and 47 in the ends of the porcelain rod 43. A series of three set screws 48 in the cap 44, and 49 in the cap 45, are projected inwardly into the grooves 46 and 47, respectively, to hold the mounting caps on the ends of the hollow rod 43.

The caps have threaded studs 50 and 51 extending axially therefrom. The stud 51 is threaded into a collar 52 which, in turn, is threaded into the threaded boss 53 in the inside bottom wall of the cap ferrule 2. The mounting member 45 has a terminal screw 54 which receives under its head the end of the wire resistor 25, and which has its shank extending into an opening 55 formed in the hollow rod 43 in the bottom of the groove 47. The extension of the shank of the screw 54 into said opening 55 prevents the mounting member 45 from turning on the rod 43.

In like manner, the front end of the resistor wire 25 is clamped under the end of the terminal screw 56, which has its shank projected into the opening 57 in the bottom of the groove 46 to prevent the mounting member 44 from turning on the hollow rod 43.

The axially extending boss 50 on the mounting member 44 projects loosely through a hole in the cross bar or spider 26, the construction of which is similar to that shown

in connection with Figs. 1 to 5, inclusive. In this case, however, I provide a square annular shoulder at 58 so that the end of the cross bar or spider 26 lies flat against the bottom of the shoulder and is held in place by suitable screws like the screws 28 shown in Fig. 5. In a similar manner, electrically, the boss 50 is connected to the sleeve ferrule 4 by means of a flexible metallic ribbon 30, the ends of which are mounted on the shoulder 58 by means of the screws 33.

The cap member 12 and its manner of closing the end of the sleeve ferrule 4 at the top of the unit is as described in connection with the device of Figs. 1 to 5.

The braid or ribbon 30 is likewise fastened to the hub 50 by a screw 31 and washer 32.

The form of mounting shown in Figs. 8 to 10, inclusive, is applicable to all forms in which the resistor wire is of relatively small diameter, that is, is fine wire.

In Fig. 11 I have shown a resistance unit of relatively large current carrying capacity and relatively small resistance, for example, of 5 amperes maximum capacity and 2 ohms resistance.

In this construction, the glass sleeve 1 and the metallic ferrules 2 and 4 with their immediately connected parts are identical with the structure shown in Figs. 1 to 5, inclusive. The porcelain core or rod 60 has a helical groove for receiving the ribbon resistor 61, which, in the present case, is of the order of $\frac{1}{8}$ th inch wide and approximately .045 in. thick nichrome wire wound in a straight helical coil of approximately $\frac{7}{8}$ ths inch inside diameter.

The porcelain core 60 has plain cylindrical ends with transverse openings therethrough for receiving the threaded terminal 105 plugs 62 and 63 which pass loosely through the openings in the core, but are threaded into transverse openings in the short mounting rods 64 and 65.

The plugs 62 and 63 are drilled and tapped throughout the major part of their length to receive the set screws or binding screws 66 and 67. Transverse openings or bores 68 and 69 are formed through the remote ends of the screw plugs 62 and the ends of the resistor are projected through said openings 68 and 69 and are gripped therein by the binding screws 66 and 67 to form a firm mounting on the core 60, preventing the resistor from uncoiling and making electrical connection with the mounting rods 64 and 65 which are substantially like the mounting rods 19 shown in Fig. 4.

The rod 65 is threaded into the hollow boss 13, the inside of the cap ferrule 2, and the rod 64 is passed loosely through the spider 26, which has its ends 27 fastened by machine screws 28, as shown in Fig. 5, to the sloping shoulder 9.

The end of the mounting rod 64 is con-

nected to a flexible braid connection 30, as described in connection with Figs. 4 and 5. The closure cap 12 hermetically seals the end of the ferrule 8 and closes the unit.

5. In each construction, the resistor is enclosed in a hermetically sealed weather tight casing, one end being anchored to one ferrule and the other end being permitted to have endwise play for expansion and contraction with a flexible connecting lead or terminal joining the said free end of the resistor with the other ferrule.

The outside casing, that is, the glass sleeve and terminals and caps, being substantially identical with the well known form of sleeve above referred to, requires no additional part to be carried in stock for said casing.

The resistor being held out of contact with the glass sleeve and spaced therefrom by an air space, does not subject the glass, even when the resistor is heated, to any injurious stresses.

If desired, the casing may be filled with insulating filling, such as a liquid dielectric, but I do not generally employ the same. The inherent resistance characteristics of the unit are not affected by heating, and the resistor does not deteriorate with age or service.

I do not intend to be limited to the precise details shown or described.

I claim:

1. A resistance unit comprising an insulating sleeve having a cap secured upon one end thereof, a ferrule secured on the other end, a central rod of insulation, metallic mounts for the ends of the rod, one of said mounts being secured to the cap, a spider connecting the other mount inside the ferrule, a wire resistor disposed on the rod and connected to said mounts, and a closure for the end of the ferrule.

2. In combination, a rod of insulating material, metallic mounts non-rotatably secured on the ends of said rod, a wire resistor wound upon the rod and having its ends mechanically and electrically connected to said mounts, an enclosing casing of insulation having metallic terminals thereupon forming closures for the casing, one of said mounts being connected rigidly, mechanically and electrically to one of said terminals, the other of said mounts being connected to another terminal electrically and supported radially to permit endwise expansion and contraction of the rod.

3. In combination, a rod of insulation, a wire resistor wound on the same, metallic mounts having studs extending from the ends of the rod, said mounts being non-rotatably secured to the rod, an enclosing sleeve of insulation having a cap ferrule at one end and having a threaded socket for receiving one of said studs, a sleeve ferrule on the other end of the sleeve, a spider in said latter ferrule supporting the other stud radially, a

flexible lead connecting the said stud and said sleeve ferrule, and a closure for the end of the sleeve ferrule.

4. In combination, a hollow rod of insulating material having a wire resistor wound thereupon, short metallic mounting rods lying loosely in the ends of the bore of the hollow rod, the ends of the hollow rod having diametrical openings therethrough, and terminal screws threaded into said mounting rods and lying in said diametrical bores, said terminal screws lying loosely in said diametrical openings and connecting the ends of the wire resistor to said mounting rods.

5. A resistance unit comprising a central core of insulation, an electric resistor supported thereby, said core having a longitudinal bore at each end, short conducting rods inserted one in each bore, means for preventing the withdrawal of the rods, said means permitting a limited amount of free movement between at least one of the rods and the core, an electrical connection between the rods and the respective ends of the resistor, a sleeve of insulating material around the resistance unit, and metallic ferrules closing the end of the sleeve, one of said rods being threaded into and supported by one of said ferrules.

6. An electric apparatus comprising an enclosing tube, an insulating core within the tube, current conducting means mounted on said core, said core having a central longitudinal bore at the end thereof, a rod having one end inserted into the bore, said core having a radial opening therein adjacent the longitudinal bore, a screw passing through the radial opening and threaded into the rod, said opening being of appreciably larger diameter than the diameter of the screw thereby permitting a limited free sidewise movement of the screw in the radial hole and a similar longitudinal movement of the rod, said current conducting means being connected to said rod through said screw, and means for supporting the other end of the rod within the tube thereby supporting the core.

7. A resistance unit comprising an insulating sleeve having a cap secured upon one end thereof, a ferrule secured on the other end, a central rod of ceramic insulation, metallic mounts for the ends of the rod, one of said mounts being secured to the cap, a spider connecting the other mount inside the ferrule, a wire resistor disposed on the rod and connected to said mounts, said mounts including means cooperating with the rod to provide yielding connections therebetween, and a closure for the end of the ferrule.

8. A resistance unit comprising an insulating sleeve having a cap secured upon one end thereof, a ferrule secured on the other end, a central rod of ceramic insulation, metallic mounts for the ends of the rod, one of said

- mounts being secured to the cap, a spider connecting the other mount inside the ferrule, a wire resistor disposed on the rod and connected to said mounts, said mounts including
- 5 means providing yielding mechanical connections between the rod and the mounts, and providing electrical connections between the resistor and the mounts, and a closure for the end of the ferrule.
- 10 9. In combination, a rod of insulating material, metallic mounts non-rotatably secured on the ends of said rod, a wire resistor wound upon the rod, said mounts including means cooperating with the rod to provide yielding
- 15 connections therebetween, an enclosing casing of insulation having metallic terminals thereupon forming closures for the casing, one of said mounts being connected rigidly, mechanically and electrically to one
- 20 of said terminals, the other of said mounts being connected to another terminal electrically and supported radially to permit endwise expansion and contraction of the rod.
10. In combination, a rod of insulating ma-
- 25 terial, metallic mounts non-rotatably secured on the ends of said rod, a wire resistor wound upon the rod, said mounts including means providing yielding mechanical connections between the rod and the mounts, and provid-
- 30 ing electrical connections between the resistor and the mounts, an enclosing casing of in-
- 35 sulation having metallic terminals thereupon forming closures for the casing, one of said mounts being connected rigidly, mechanical-
- 40 ly and electrically to one of said terminals, the other of said mounts being connected to another terminal electrically and supported radially to permit endwise expansion and con-
- traction of the rod.
- 40 In witness whereof, I hereunto subscribe
my name this 24th day of January, 1928.
- NICHOLAS J. CONRAD.
